US00D993976S

(12) **United States Design Patent** (10) Patent No.: **US D993,976 S**
(45) Date of Patent: **** Aug. 1, 2023**

(54) **ELECTRONIC DEVICE WITH ANIMATED GRAPHICAL USER INTERFACE**

(71) Applicant: **Apple Inc.**, Cupertino, CA (US)

(72) Inventors: **Benjamin Thomas Christie**, Santa Clara, CA (US); **Anton Davydov**, Gilroy, CA (US); **Frank K. F. Lee**, Toronto (CA); **Daniel J. Wiersema**, San Jose, CA (US)

(73) Assignee: **Apple Inc.**, Cupertino, CA (US)

(**) Term: **15 Years**

(21) Appl. No.: **29/845,821**

(22) Filed: **Jul. 11, 2022**

Related U.S. Application Data

(63) Continuation of application No. 29/803,208, filed on Aug. 11, 2021, now Pat. No. Des. 957,423, which is a continuation of application No. 29/702,393, filed on Aug. 19, 2019, now Pat. No. Des. 928,180, which is a continuation of application No. 29/625,171, filed on Nov. 7, 2017, now Pat. No. Des. 857,033.

(57) **CLAIM**

The ornamental design for an electronic device with animated graphical user interface, as shown and described.

DESCRIPTION

FIG. 1 is a front view of an electronic device with animated graphical user interface showing a first image of the claimed design;

FIG. 2 is a second image thereof;

FIG. 3 is a third image thereof; and,

FIG. 4 shows an environmental electronic device to which the design of FIG. 1 may be applied. The animated graphical user interface designs of FIGS. 2-3 may be similarly applied thereto.

The outer broken lines in the figures show a display screen or portion thereof, or an electronic device having a display screen, and form no part of the claimed design. The other broken lines in the figures show portions of the animated graphical user interface that form no part of the claimed design.

The appearance of the animated image sequentially transitions between the images shown in FIGS. 1-3 Figures. The process or period in which one image transitions to another forms no part of the claimed design.
